REDUCTION OF ORGANIC COMPOUNDS

Arthur L. Fox, Woodstown, N. J., assignor to E. I.
du Pont de Nemours & Company, Wilmington,
Del., a corporation of Delaware

No Drawing. Application March 25, 1942,
Serial No. 436,205

8 Claims. (Cl. 260—609)

This invention relates to the production of mixtures of aliphatic mercaptans. More particularly, it relates to the production of mixtures of saturated aliphatic mercaptans from mixtures of saturated aliphatic sulfonylhalides. Still more particularly, it relates to the production of mixtures of saturated aliphatic mercaptans of at least 5 and preferably at least 8 carbon atoms from mixtures of saturated aliphatic sulfonyl chlorides of the same number of carbon atoms. The invention also relates to mixtures of novel mercaptans obtainable by such processes.

In one of its aspects the invention pertains to the production of mixtures of saturated aliphatic mercaptans containing a plurality of mercapto groups in the molecule from mixtures of saturated aliphatic polysulfonyl chlorides of at least 8 carbon atoms and to the products produced thereby.

In another aspect the invention is concerned with the production of mixtures of such aliphatic mercaptans containing chloro aliphatic mercaptans from mixtures of saturated aliphatic hydrocarbon and chlorohydrocarbon mono- and polysulfonyl chlorides and mixtures of such sulfonyl chlorides containing at least 8 carbon atoms and to the mixtures of novel mercaptans obtainable thereby.

It is an object of this invention to produce new and useful mixtures of mercaptans. A further object is to produce mercaptans from hydrocarbon sulfonyl chloride derivatives. A more specific object of this invention is to produce mixtures of higher aliphatic mercaptans by reducing them in the liquid phase with a strong reducing agent. Another object is to provide a new use for petroleum sulfonyl chloride derivatives. Yet another object is to provide a simple and economical means of producing such aliphatic mercaptans. Still other objects will be apparent from the following description of the invention.

The above objects of the invention may be accomplished by the following invention which comprises reducing a mixture of homologous saturated aliphatic sulfonyl chloride derivatives with a strong reducing agent until at least a recoverable amount of mercaptan derivatives is formed. The mercaptans can then be recovered and utilized and the remaining sulfonyl chlorides further reduced with the addition of further sulfonyl chlorides and/or reducing agents. The reaction may, for instance, be allowed to proceed until a substantial amount of the mixture of aliphatic mercaptans separates out. It may be recovered from the reaction mass

and purified by various physical and/or chemical methods.

The reaction can be carried out in an aqueous or nonaqueous medium. In the former, the homologous mixtures of aliphatic sulfonyl chlorides of at least 5 carbon atoms can be dispersed in water at normal or moderate temperatures, admixed with an acid, e. g. hydrochloric, sulfuric, acetic, etc., and a finely divided heavy metal, 5 and the reaction mass heated to a moderate temperature. Suitable finely divided metals include zinc, iron and tin.

A preferred method of carrying out the invention resides in the use of a non-aqueous medium. 15 In this preferred aspect of the invention an inert solvent or diluent is used and the reduction effected by means of hydrogen in the presence of a hydrogenation catalyst. The mixture of saturated aliphatic sulfonyl chlorides of at least 5 20 carbon atoms may be admixed with the solvent and catalyst and hydrogen passed in. Mechanical agitation to keep the catalyst uniformly distributed may be availed of. When the reduction has been carried out to completion or to the desired extent the mercaptan derivatives can be separated out by adding water, extraction, and/or decantation and further purified by the methods outlined above.

The latter reduction may be carried out in a 30 pressure vessel at temperatures from 50 to 200° C. and more. It has the advantage that the absence of water insures against the hydrolysis of the sulfonyl chloride derivatives to sulfonic acids. Solvents such as benzene, toluene, xylene, 35 carbon tetrachloride, benzine, pentane, hexane, etc. can be used as reaction media.

It has been found that the organic sulfonyl chloride mixtures obtained by reacting saturated aliphatic hydrocarbons of at least 8 carbon 40 atoms including mixtures of such hydrocarbons, such as petroleum fractions, paraffin waxes, etc. with admixed sulfur dioxide and chlorine under conditions conducive of the formation of organic sulfonyl chlorides, can be converted into 45 useful mercaptans by the above procedures. The preparation of the initial materials is described in U. S. Reissue 20,968, and in 2,202,791. In general, a complex homologous mixture of primary and secondary hydrocarbon and chlorohydrocarbon mono- and poly-sulfonyl chlorides predominating in secondary sulfonyl chlorides are formed by the processes described in said 50 patents.

The proportions of such ingredients can be 55 varied by varying the reactants and conditions.

The mercaptans from mixtures predominating in polysulfonyl chloride derivatives and/or containing high percentages of chlorine atoms attached to a carbon are quite unique and constitute important aspects of the invention.

The invention will be further illustrated but is not intended to be limited by the following examples.

Example I

Thirty-five parts of zinc dust, 87 parts of water and 38 parts of a homologous mixture of cetane sulfonyl chlorides, containing and consisting of cetane and chlorocetane, primary and secondary mono- and polysulfonyl chlorides, 23.65% chlorine and 12.21% sulfur, prepared according to the teachings of U. S. patent, Reissue 20,968, while irradiating with light from a tungsten filament light bulb, were admixed and heated on a water bath, the temperature rising to 80° C. before the outside temperature reached 60° C. After the reaction mass had been cooled to 60° C., 418 parts of zinc dust was added and it was kept at 60° C. for 3 hours and then cooled to 20° C. and 222 parts of hydrochloric acid (concentrated) was added. The temperature was raised to the boil and kept there for 2 hours during which time 22.7 parts zinc dust was added in small amounts. The reaction mass was then stirred for 12 hours and the water-white upper oily layer of a mixture of cetane- and chlorocetane-mercaptans was separated. Analysis: chlorine, 7.35%; sulfur, 14.84%. Five parts of the homologous mixture of cetane mercaptan derivatives was dissolved in 50 parts warm alcohol and treated with an alcoholic solution of mercuric chloride. A white precipitate of the mercuric mercaptide formed at once.

Example II

Seventy parts zinc dust, 180 parts water and 200 parts of a homologous mixture of petrodatum sulfonyl chlorides, including primary, secondary and chloro-sulfonyl chlorides, containing 7.44% sulfur and 18.55% chlorine obtained by reacting petrodatum with admixed sulfur dioxide and chlorine after the manner set forth in U. S. Patent 2,202,791, were mixed and stirred together for 2 hours. There was then added 10 parts zinc dust and the reaction mass stirred for 16 hours at room temperature, then 440 parts concentrated HCl was added and the reaction mass refluxed 36 hours. The light colored oil containing petrodatum mercaptan derivatives including chloro petrodatum mercaptans was separated.

Example III

Thirteen hundred and five parts water and 525 parts zinc dust were mixed with 570 parts of a homologous mixture of cetane and chlorocetane sulfonyl chlorides including mono- and polysulfonyl primary and secondary derivatives containing 8% sulfur and 24.2% chlorine obtained after the manner described in Example I. The reaction mass warmed up to 70° C. spontaneously. At this point 72 parts of zinc dust was added and the mass stirred at 60° C. for 2 hours and then 3320 parts hydrochloric acid was gradually added over a period of 2 hours. The temperature rose to the boil and 340 parts zinc dust was added in small portions over the next 2 hours. The reaction mass was then heated at 100° C. for 36 hours. The zinc was not completely dissolved at this point and the liquid was decanted and the upper oily layer separated. This

was vacuum distilled and some water and some sulfur dioxide was first removed. The material was fractionated according to the following table:

Fraction	Boiling point °C.	Pressure Mm.	Sulfur Percent	Chlorine Percent	Purity by SH	Iodine No.
10	Up to 180	0.5	4.0	4.99	Not run	88
	160-180	0.3	3.9	3.72	Not run	106
	140-160	0.1	7.76	3.63	Not run	111
	160-180	0.1	11.49	4.91	55.5	90
	180-230	0.1	14.77	1.20	56.1	82

From this table it is apparent that this reduction also removes a considerable portion of the chain halogen and leaves in its place an unsaturated mercaptan.

20

Example IV

Two hundred parts of a refined #40 white oil sulfonyl chloride obtained after the manner described in U. S. P. 2,202,791 (Example I) containing alkane and chloroalkane primary and secondary mono- and poly-sulfonyl chlorides was introduced into an autoclave with 1000 parts benzene, 200 parts MgO and 100 parts reduced nickel catalyst. The charge was reduced at 150° C. under 700 lbs. of hydrogen for 2.5 hours after the last pressure drop. The solids comprising catalyst were filtered off. SH analysis of the benzene solution indicated 1.99% SH, which corresponds to a yield of 77% of white oil mercaptan.

25 In place of the nickel catalyst of Example IV may be substituted other hydrogenation catalysts including palladium, platinum, copper, copper-chromite. Other acceptors such as calcium oxide can be used in place of magnesium oxide.

30 Still other useful acid acceptors include barium oxide, calcium hydroxide, and barium hydroxide.

In place of the high molecular weight sulfonyl chlorides set forth in the above examples may be substituted other sulfonyl chloride derivatives obtainable from saturated aliphatic hydrocarbons of at least 5 and preferably at least

35 8 carbon atoms including mixtures of such hydrocarbons such as petroleum hydrocarbon fractions. Thus, the homologous mixtures of sulfonyl chloride derivatives obtainable from pentane, octane, nonane, decane, dodecane, octadecane, etc., refined kerosene, lubricating oils, white oils, etc.; paraffin wax, scale wax, wax distillates, match wax, Asiatic wax, etc., and the saturated hydrocarbon mixtures obtained by practicing the processes described in British Patent 511,614 can be used as reactants. The petroleum hydrocarbon fractions may contain naphthene hydrocarbons of 8 to 18 carbon atoms in various proportions.

40 60 Sulfonyl chloride derivatives free from chlorine attached to carbon as well as those containing such atoms are comprehended. Such derivatives are not limited to those prepared by the process of Reed U. S. Reissue Patent 20,968. On the contrary, similar products can be made from sulfonyl chloride and actinic light irradiation after the manner described in J. Am. Chem. Soc. 61, 3089-91, (1939). Other processes of 45 making mixtures of primary and secondary sulfonyl chloride products free from chlorine attached to carbon are described in U. S. Patents 2,146,744, 2,147,346 and 2,142,934.

55 This invention provides a smooth and economical route for the conversion of cheap paraf-

fin hydrocarbons to mixtures of mercaptans. These mercaptans may find use for the preparation of surface active chemicals or for conversion to metal mercaptides which are of value as insecticides, fungicides, bactericides and lubricating oil addition agents.

As many apparently widely different embodiments of this invention may be made without departing from the spirit and scope thereof it is to be understood that I do not limit myself to the specific embodiments thereof except as defined by the appended claims.

I claim:

1. The process which comprises reacting a mixture of saturated hydrocarbon sulfonyl chlorides of at least 5 carbon atoms free from aromatic groups with a strong reducing agent and recovering a mixture of mercaptans.

2. The process which comprises reacting a mixture of saturated aliphatic hydrocarbon sulfonyl chlorides of at least 8 carbon atoms free from aromatic groups with a strong reducing agent at a temperature from 20 to 250° C. until a material amount of the sulfonyl chloride has been converted to a mercaptan.

3. The process which comprises reacting a mixture of saturated aliphatic hydrocarbon primary and secondary sulfonyl chlorides of at least 8 carbon atoms free from aromatic groups with a strong reducing agent in a mineral acid media at a temperature from 20 to 250° C. until a material amount of the sulfonyl chloride has been converted to a mercaptan.

4. The process which comprises reacting an

isomeric mixture of primary and secondary alkane polysulfonyl chlorides and chloroalkane sulfonyl chlorides of at least 8 carbon atoms with a strong reducing agent at a temperature from 5 20 to 250° C. until a material amount of the sulfonyl chlorides have been converted to mercaptans.

5. The process which comprises reacting a homologous and isomeric mixture of primary and secondary alkane sulfonyl chlorides of at least 10 eight carbon atoms in the hydrocarbon nuclei with a finely divided heavy metal in a dilute mineral acid solution at a temperature from 20 to 250° C. until a material amount of the sulfonyl 15 chloride groups has been converted to mercaptan groups.

6. The process which comprises reacting a mixture of saturated hydrocarbon sulfonyl chlorides of at least 5 carbon atoms free from 20 aromatic groups with hydrogen in the presence of a hydrogenation catalyst.

7. The process which comprises reacting a mixture of saturated hydrocarbon sulfonyl chlorides of at least 5 carbon atoms free from 25 aromatic groups with hydrogen in the presence of a nickel catalyst.

8. The process which comprises reacting a mixture of petroleum white oil primary and secondary sulfonyl chlorides containing chlorine 30 groups attached to carbon in a benzene solution with hydrogen in the presence of an acid acceptor and a reduced nickel catalyst.

ARTHUR L. FOX.
